TOOTHBRUSH

Oskar Gruenwald, Jackson Heights, N.Y.

Application October 4, 1956, Serial No. 613,868

3 Claims. (Cl. 15—167)

The present invention relates to toothbrushes and in particular to toothbrushes which are operated with one finger in order to permit of a thorough cleansing action of the teeth.

It has been proposed before to provide toothbrushes which instead of providing a conventional handle were equipped with a rubber ring at its outer end which was adapted to receiving one finger and furthermore it has been also proposed before to provide a holder of frustoconical configuration adapted to receive a finger or even to provide merely a finger sleeve made of rubber which was formed on its outside with a series of ridges designed to perform the cleansing action on the teeth.

While these known structures amounted already to an improvement of the conventional toothbrush, it was unavoidable that all known structures required the manufacture of different sizes because the holder, sleeve or the like had to conform to the thickness of the finger of the user of the toothbrush.

It is, therefore, one object of the present invention to provide a toothbrush which is designed to be handled with one finger only and permits of a cleansing action on the inside and outside of the teeth and which is equipped with a member which is adjustable to any thickness of the finger of the user.

It is another object of the present invention to provide a toothbrush which comprises a short handle to which bristles or the like are secured and one end of said handle has attached thereon one end of a helical spring made of such material that the spring adjusts itself to the thickness of the finger merely by insertion of the finger into the helical spring.

With these and other objects in view which will become apparent in the following detailed description, the present invention will be clearly understood in connection with the accompanying drawing, in which:

Figure 1 is a side elevation of the toothbrush with the finger shown in a straight position;

Fig. 2 is a side elevation of the toothbrush with the finger in bent position to indicate the possibility of reaching the inner faces of the teeth;

Fig. 3 is a bottom plan view of the toothbrush as shown in Fig. 1; and

Fig. 4 is a section along the lines 4—4 of Fig. 2.

Referring now to the drawing, the toothbrush comprises a handle on stem 1 which carries at one end thereof a plurality of bristles 2. The other end of the handle 1 has a bore 3 slightly spaced apart from its extreme end and the periphery of the end portion of the handle 1 has a spiral groove adapted to receive the end coils of a helical spring 4, while the end of the spring 4 has a short linear portion 5 which is received in the hole 3 of the handle 1. The spring 4 is made of such material that the diameter thereof is reduced upon extension of the spring 4, while its diameter is increased upon compression of the spring 4. By this arrangement it is rather simple to accommodate the spring 4 to any thickness of the finger

2

of the user and it is merely necessary to produce one model which can be used by children as well as by adults in the same manner. Due to the simple means of securing one end of the spring 4 to the handle 1 it is possible also to remove the spring 4 from the handle 1 and replace the spring 4 by a new spring if such replacement is required, for instance, in case the elasticity of the spring has worn out. The spring may be made of any non-rusting metal, hard rubber, plastic, nylon or the like, yet the wire used for the formation of the spring must be of comparatively thin cross section to permit of bending of the finger inserted therein in order to be able to reach into the mouth and brush the inner faces of all teeth. Such arrangement makes it possible to clean the teeth at their entire circumference up to the gum and also reach the spaces between each pair of adjacent teeth.

It has been found also of advantage to arrange the longitudinal axis of the handle relative to the longitudinal axis of the spring 4 at an angle α of substantially 15° (see Fig. 1), because it has been found that such angular arrangement of the toothbrush relative to the spring simplified the engagement of the teeth by the brush.

While the specific connecting means between the handle 1 and the spring 4 has been disclosed, it is to be understood that any other suitable means for connecting of these elements may be used.

While I have disclosed one embodiment of the present invention, it is to be understood that this embodiment is given by example only and not in a limiting sense, the scope of the present invention being determined by the objects and the claims.

I claim:

1. A toothbrush comprising a short stem carrying a plurality of bristles at one end thereof, a helical spring adapted to receive one finger of the user of said brush, the other end of said stem having a bore receiving one end of said spring and having a spiral groove receiving the end coils of said helical spring, to provide a rigid connection between said stem and said spring and to permit of easy access to all parts of the teeth, and said helical spring changing its diameter upon extension and compression, respectively, in order to adjust the open diameter of said spring to the thickness of the finger of the user of said brush.

2. A toothbrush comprising a short stem carrying a plurality of bristles at one end thereof, a helical spring adapted to receive one finger of the user of said brush, means rigidly connecting the other end of said stem with one end of said spring, and said helical spring changing its diameter upon extension and compression, respectively, in order to adjust the open diameter of said spring to the thickness of the finger of the user of said brush.

3. A toothbrush comprising a short stem carrying a plurality of bristles at one end thereof, a helical spring adapted to receive one finger of the user of said brush, means wrapped around and extending through the other end of said stem for connection of the latter with one end of said spring, and said helical spring changing its diameter upon extension and compression, respectively, in order to adjust the open diameter of said spring to the thickness of the finger of the user of said brush.
